UNITED STATES PATENT OFFICE

PIERRE LE SUR, OF BELFORT, FRANCE, ASSIGNOR TO GENERAL ELECTRIC COMPANY,
A CORPORATION OF NEW YORK

POWER INSTALLATION

Application filed June 5, 1930, Serial No. 459,277, and in France June 13, 1929.

The present invention relates to power installations comprising a steam boiler and a steam turbine of the type wherein during periods of lesser load on the installation 5 water heated by steam generated in the boiler is stored in a tank or tanks and utilized for feeding the boiler during periods of maximum load.

The object of my invention is to provide 10 an improved system or arrangement in an installation of this type, and for a consideration of what I believe to be novel and my invention attention is directed to the following specification and the claims appended 15 thereto.

In the drawings, Fig. 1 is a diagrammatic view of an installation embodying the invention; Fig. 2 is a diagram showing the results obtained by utilization of the invention; and 20 Figs. 3 and 4 are views similar to Fig. 1 of other embodiments of the invention.

Referring to Fig. 1 of the drawings, 1 indicates diagrammatically a steam boiler or 25 elastic fluid generating means having a superheater 2 and a feed water or level regulator 3 which controls the supply of water or liquid to the boiler. The feed water regulator is indicated only diagrammatically, but it is to be understood that the diagram indicates any suitable type of feed water regulator controlled by the level of the water in the boiler or by other means. 4 indicates an 30 elastic fluid turbine which receives steam from the boiler 1 through conduit 5 and which exhausts to a condenser 6. Connected 35 to the condenser is a condensate pump 7 which delivers condensate to a feed water heater or pre-heating means 8 of the surface type. From feed water heater 8 the feed water 40 is delivered by a pump 9 to a second feed water heater 10 of the surface type, and from feed water heater 10 the feed water is delivered by a boiler pump 11 through conduits 45 11^a and 11^b to the boiler 1, the delivery being under the control of the feed water regulator 3. The feed water heaters 8 and 10 are supplied with elastic fluid extracted from intermediate stages of the turbine 4, the feed 50 water heater 10 being connected to a higher pressure stage of the turbine by a conduit

12, and feed water heater 8 being connected to a lower pressure stage of the turbine by a conduit 13. Thus there is supplied to the feed water heater 10 steam of a temperature higher than that which is supplied to the 55 feed water heater 8. The heating steam condensed in feed water heaters 8 and 10 is discharged through pipes 14 and 15 to the inlet of a pump 16 which in turn delivers the water to the inlet of pump 9 through the discharge pipe 17.

The arrangement of installation wherein the feed water on its way from the condenser to the boiler is heated by steam extracted from a plurality of stages of the turbine is 60 65 known.

According to the embodiment of my invention illustrated in Fig. 1, I provide a storage water tank or drum 18 for the storage of hot water to be used in feeding the 70 boiler, the tank being connected to pipe 11^a by a pipe 19. In pipe 11^a and in advance of the connection of pipe 19 therewith as regards the direction of flow, there is provided a valve means 20 which is actuated in response to the rate of flow of steam through the conduit 5, that is, to the load on boiler 1. When the load on boiler 1 is below a predetermined value, valve means 20 is open, and when the load increases beyond such predetermined value, valve means 20 is closed. In the present instance the valve means is shown diagrammatically as comprising a valve head 21 having its stem connected to a diaphragm 22 contained in a casing 23, the upper portion of the casing being connected by a pipe 24 to a device responsive to the rate of flow of steam through conduit 5, such device being indicated diagrammatically in the present instance as comprising a tube 25. Beneath the diaphragm is located an adjustable spring 25^a. It will thus be seen that diaphragm 22 is subjected on its upper side to the pressure conveyed to it by pipe 24, and on the lower side to the pressure of spring 25^a. The arrangement is such that when the flow increases beyond a predetermined value the pressure in pipe 24 becomes sufficient to force valve head 21 on to its seat. With this arrangement, when the valve means 20 is open 80 85 90 95 100

the pumps 7, 9 and 11 supply hot water to the storage tank 18 and to the boiler 1, the storage tank 18 taking the water in excess of that required for the boiler. When the load on boiler 1 exceeds a predetermined amount, valve means 20 is closed, whereupon the pump 11 supplies water to the boiler from storage tank 18.

At 26 is an equalizer tank or reservoir connected by a pipe 27 to the discharge side of pump 7. Makeup water or liquid for the system is supplied to equalizer tank or reservoir 26 through a pipe 28 in which is a control valve 29. Valve 29 is regulated in a manner such that when the combined supply of water in tanks 18 and 26 decreases below a certain amount, valve 29 is opened to admit makeup water or liquid to the tank 26. As a means of accomplishing this, I have shown diagrammatically the valve 29 as being connected to one end of the lever 30 pivoted at 31. The other end of lever 30 is connected by a three-arm link 32 to two containers 33 and 34. The container 33 is connected to tank 18 at vertically spaced points by means of flexible tubular connections 35, and the container 34 is connected to tank 26 at vertically spaced points by flexible tubular connections 36. By this arrangement, there is present in the containers 33 and 34 a quantity of water or liquid corresponding with the levels or depth of the water in tanks 18 and 26. The containers 33 and 34 with the water therein constitute in substance a weight attached to the left-hand end of lever 30, the value of which varies in accordance with the levels or depth in tanks 18 and 26. The weights are opposed by a spring 37. 38 is a stop for limiting the upward movement of the left-hand end of lever 30. With this arrangement, as long as the level of water in tanks 18 and 26 is above the predetermined height, the weight of the water in containers 33 and 34 is sufficient to hold valve 29 closed against the action of spring 37. When the level of water in either or both of the tanks decreases to a point where the combined weight of the containers 33 and 34 decreases below a certain value, spring 37 will lift the left-hand end of lever 30 thereby opening valve 29 and admitting makeup water to the equalizer tank through inlet pipe 28 until its level is raised to an extent such that the additional weight of water in container 34 which indicates the amount of water in said equalizer tank will effect the closing of the valve 29. Thus, make-up liquid is supplied through conduit 26 in response to the change of the total amount or the total depth of liquid in both tanks 18 and 26, depending upon the relative sizes of the two tanks and the containers 33 and 34 respectively.

During normal operation at loads below the predetermined maximum which effects the closing of the valve means 20, water may

be taken from equalizer tank 26 along with the condensate from condenser 6 for the supply of the boiler and for filling the tank 18. During this operation the level of the liquid in equalizer tank 26 may be decreased to a considerable extent, while that in the tank 18 is increased. When valve means 20 is closed due to increase in the load on the boiler beyond the predetermined value, the boiler then being fed from storage tank 18, as already described, the condensate from condenser 6 is then discharged by the pump 7 to the equalizer tank 26, the condensate being thus stored in the equalizer tank while the hot water is being used from the storage tank 18. As a result of this, condensate will no longer flow through the surface feed water heaters 8 and 10 with the result that the pressure in conduits 14, 15, 17, 12 and 13 increases and prevents further extraction of steam from turbine 4. As a result, all the steam supplied to the turbine through conduit 5 will pass through the turbine to the condenser, no steam being extracted from the turbine. This means that with the same amount of steam supplied to the turbine as before, the turbine will be able to carry a greater load because of the fact that all the steam is passing entirely through the turbine to the condenser. This will be clear when it is considered that only a part of the energy of the steam taken from the turbine through pipes 12 and 13 is extracted in the turbine, the remainder of the energy being returned to the feed water in the form of heat.

It will thus be seen that by my invention, during periods when the load is below a predetermined high value, I extract elastic fluid from one or more stages of the turbine for feed water heating, at the same time storing hot water, and when the load on the boiler exceeds a predetermined high value I cease extracting steam from the turbine for feed water heating, whereby all the energy of the steam may be utilized in carrying the load on the turbine, the boiler being then fed with the hot water previously stored in the hot water storage tank. The capacity of the tank 18 is made sufficiently great to take care of the anticipated consumption of steam during the longest period of maximum output to be met with and the equalizer tank 26 is large enough to hold the additional water during said period.

The diagram in Fig. 2 illustrates the results obtained by utilizing the invention. The curve A indicates the variation in turbine load plotted against time. The curve B gives for each instant the corresponding consumption of steam for an installation provided with a usual arrangement of continuous feed water preheating by extracted steam. The curve C shows the effect of eliminating the extraction of steam from the tur-

bine during the period of maximum load output, that is, during the period from D to E. A comparison of the curve C with the curve B indicates clearly that during the period of maximum load from D to E a substantially lesser amount of steam is required for carrying the load due to preventing the extraction of steam from the turbine. The amount of water accumulated in reservoir 26 during this period is represented by the cross-hatched area F.

In Fig. 3 is illustrated an embodiment of my invention wherein the heating steam for heating the feed water is supplied not from a stage or stages of the main turbine but by means of a separate feed water heating or auxiliary turbine provided with a special regulating device.

Referring to Fig. 3, 40 indicates a boiler similar to the boiler 1 of Fig. 1 which supplies steam through the pipe 41 to main condensing steam turbine 42, the condenser for which is indicated at 43. 44 indicates the condensate pump which delivers condensate from condenser 43 to the surface feed water heaters 45 and 46 corresponding to the feed water heaters 8 and 10 of Fig. 1. 47, 48 and 49 are pumps corresponding in function and arrangement to the pumps 9, 16 and 11 of Fig. 1, and 50 is a load control valve means corresponding to the load control means 20 of Fig. 1. Also, 51 and 52 are hot water storage tank and equalizer tank corresponding to the tanks 18 and 26 of Fig. 1, and equipped with a similar mechanism for supplying makeup water to the equalizer tank 52.

According to my invention as illustrated in Fig. 3, I provide an auxiliary turbine 53 for supplying heating steam to the feed water heaters 45 and 46, the feed water heater 45 being supplied with the exhaust steam from turbine 53 through a pipe 54, and the feed water heater 46 being supplied with steam from an intermediate stage of turbine 53 through pipe 55. Turbine 53 is supplied with steam from pipe 41 through a pipe 56 in which is arranged a valve means 57 controlled in accordance with the pressure in the steam in pipe 55. By this means, there is supplied always steam of suitable pressure to the feed water heaters 45 and 46. In the present instance valve means 57 is shown as being controlled by diaphragm 58 subjected to the pressure in pipe 55 through a pipe 59, the arrangement being such that valve 58 is moved toward closed position as the pressure increases and is permitted to open as the pressure decreases. It will be understood, of course, that this showing is of a diagrammatic character and that any suitable pressure control valve mechanism may be used for controlling turbine 53. Also, it will be understood that the speed of turbine 53 will be fixed in some suitable way such as by having its generator tied in on the

same line with other alternating current generators.

With the foregoing arrangement, steam is supplied by the boiler 40 for operating the turbine 42 and also for feed water heating, the energy of the steam for feed water heating being utilized partially in the auxiliary turbine 53. When the load on the boiler exceeds a predetermined value, valve means 50 is closed as heretofore explained in connection with Fig. 1. As a result, the feed water heaters 45 and 46 cease utilizing heating steam so that the pressure in pipe 55 builds up thereby closing the valve means 57 so that all the steam generated by boiler 40 may be supplied directly to the main condensing turbine 42. During this period of time, heating of feed water by steam ceases, the boiler is supplied with hot water from the tank 51, and the condensate is stored in the equalizer tank 52 as explained in connection with Fig. 1.

During the period when valve means 50 is closed, it is desirable that some steam be passed through the auxiliary turbine 53 in order to keep it running under its own power and prevent its overheating, and the arrangement of the valve means 57 is such that a certain amount of steam will be supplied to turbine 53. During this period the exhaust from turbine 53 passes through a bypass pipe 60 and a weighted non-return valve 61 to a small pre-heater 62 arranged on the discharge side of condensate pump 44 so that this heat is supplied to the water being delivered by the condensate pump to the equalizer tank 52. 63 is a pipe through which the steam condensed in heater 62 is led to the inlet side of pump 44, there being a suitable non-return valve 64 in this pipe.

The arrangement shown in Fig. 3 has the advantage over that shown in Fig. 1 in that the pressure of the steam supplied to the feed water heaters 45 and 46 is maintained substantially constant irrespective of the load on the main turbine 42. This would not be the case with the arrangement shown in Fig. 1 because at light loads on the main turbine the pressures in the respective stages decrease. The arrangement shown in Fig. 3 is therefore more particularly adapted for installations wherein the load on the main turbine fluctuates over a considerable range. The arrangement shown in Fig. 1 is especially adapted for installations wherein the fluctuation of the load on the main turbine is not great.

My invention may be utilized to advantage also in connection with back pressure turbines. Back pressure turbines are usually of relatively small size and are not generally provided with steam extraction for pre-heating the feed water because with a back pressure cycle little, if any, gain in thermal efficiency is obtained. My invention, however,

may be applied to turbines of this type with gain in thermal efficiency. Fig. 4 shows an arrangement of this type.

Referring to Fig. 4, 70 indicates a boiler similar to the boiler 1 of Fig. 1 which supplies steam through a pipe 71 to a back pressure turbine 72. 73 indicates the exhaust conduit for turbine 72 and from which steam is supplied for industrial purposes through a branch pipe 74. Steam is also supplied from the exhaust conduit 73 by a pipe 75 to a feed water heater 76 of the surface type. In series with feed water heater 76 is a second feed water heater 77 of the surface type which is connected by a pipe 78 to an intermediate stage of turbine 72 to receive heating steam therefrom. The feed water heaters 76 and 77 correspond to the feed water heaters 8 and 10 of Fig. 1 and are provided with pumps 79, 80 and 81 and a load actuated valve mechanism 82, all similar to that described in connection with Figs. 1 and 3. Also, there is provided an arrangement of hot water storage tank 83 and equalizer tank 84 similar to that shown in Figs. 1 and 3. The steam conveyed away by pipe 74 and condensed is indicated as being returned to the equalizer tank 84 by a pipe 85. The feed water heater 76 is connected to equalizer tank 84 by a pipe 86, the equalizer tank 84 being in this arrangement the condensate tank or hot well from which water is supplied to the boiler. With the arrangement shown in Fig. 4 during normal operation feed water is supplied to boiler 70 from the tank 84 through pipe 86 and feed water heaters 76 and 77, the feed water heaters being supplied with heating steam through pipes 75 and 78. When the load on the boiler exceeds a predetermined high value, valve means 82 is closed whereupon all the steam from the boiler is supplied to turbine 72 and through pipe 74 for industrial purposes, the feed water heaters 76 and 77 now ceasing to operate and the boiler being fed with water from the hot water storage tank 83. In this connection it will be understood that the back pressure turbine 72 is provided with a regulating means responsive to the demand for exhaust steam for industrial purposes, as is well understood in connection with the operation of back pressure turbines.

In accordance with the provision of the patent statute, I have described the principle of operation of my invention, together with the apparatus which I now consider to represent the best embodiment thereof; but I desire to have it understood that the apparatus shown is only illustrative and that the invention may be carried out by other means.

What I claim as new and desire to secure by Letters Patent of the United States is:

1. In a power installation, the combination of an elastic fluid generating means, turbine means receiving elastic fluid from the

generating means, a condenser connected to the turbine means, pre-heating means for receiving and heating fluid from the condenser, means including a conduit and a valve in the conduit for conveying liquid from the pre-heating means to the generating means, means for supplying heating elastic fluid from a lower stage of the turbine means to the pre-heating means, means for conveying the heating fluid from the pre-heating means to the conduit ahead of the valve means as regards the direction of flow of fluid, and means for moving the valve to its closed position when the load on the generating means increases whereby the valve is completely closed when the load reaches a predetermined value and the supply of heating elastic fluid from a point between the generating means and a lower stage of the turbine means to the pre-heating means is prevented. 75
80
85

2. In a power installation, the combination of an elastic fluid generating means, turbine means receiving elastic fluid from the generating means, a condenser connected to the turbine means, pre-heating means for receiving and heating of the fluid from the condenser, means including a conduit and a valve in the conduit for conveying liquid from the pre-heating means to the generating means, means for supplying heating elastic fluid from a lower stage of the turbine means to the pre-heating means, means for conveying the heating fluid from the pre-heating means to the conduit ahead of the valve means as regards the direction of flow of fluid, means for moving the valve to its closed position when the load on the generating means increases whereby the valve is closed when the load reaches a predetermined value and the supply of heating elastic fluid from a point between the generating means and a lower stage of the turbine means to the pre-heating means is prevented, and a reservoir connected ahead of the pre-heating means as regards the direction of flow of fluid for receiving fluid from the condenser when the valve is closed and supplying liquid to the pre-heating means at low load of the generating means. 100
105
110

3. In a power installation, the combination of an elastic fluid generating means, turbine means receiving elastic fluid from the generating means, a condenser connected to the turbine means, preheating means for receiving and heating of the fluid from the condenser, means including a conduit and a valve in the conduit for conveying liquid from the pre-heating means to the generating means, means for supplying heating elastic fluid from a point between the generating means and a lower stage of the turbine means to the pre-heating means, means for conveying the heating fluid from the pre-heating means to the conduit ahead of the valve means as regards the direction of flow of fluid, 120
125
130

means for moving the valve to its closed position when the load on the generating means increases whereby the valve is closed when the load reaches a predetermined value and the supply of heating elastic fluid from a point between the generating means and a lower stage of the turbine means to the pre-heating means is prevented, a level regulator for the generating means, and a hot liquid storage tank connected to the conduit behind the valve as regards the direction of flow of fluid for receiving liquid from the pre-heating means and supplying liquid to the generating means in terms of level conditions in the generating means.

4. In a power installation, the combination of an elastic fluid generating means, turbine means receiving elastic fluid from the generating means, a condenser connected to the turbine means, pre-heating means for receiving and heating fluid from the condenser, means including a conduit and a valve in the conduit for conveying liquid from the pre-heating means to the generating means, means for supplying heating elastic fluid from an extraction stage of the turbine means to the pre-heating means, means for conveying the heating fluid from the pre-heating means to the conduit ahead of the valve means as regards the direction of flow of fluid, means for moving the valve to its closed position when the load on the generating means increases whereby the valve is closed

when the load reaches a predetermined value and the supply of heating elastic fluid from the extraction stage of the turbine means to the pre-heating means is prevented, a level regulator for the generating means, a hot liquid storage tank connected to the conduit behind the valve means as regards the direction of flow of fluid for receiving liquid from the pre-heaters and supplying liquid to the generating means when the valve is closed, a reservoir including a conduit connected ahead of the pre-heating means as regards the direction of flow of fluid for receiving fluid from the condenser when the valve is closed and supplying liquid to the pre-heating means at low load on the generating means, and means for supplying make-up liquid to the reservoir including a valve means, and means for actuating the valve means in terms of total depth of liquid contained in both the storage tank and the accumulator.

5. In combination with two tanks containing liquid, means for supplying make-up liquid to one of the tanks in terms of depth of liquid in both tanks, said means including a valve, a fulcrumed lever pivotally connected to the valve, two containers, each container communicating with one of the tanks whereby the liquid level in each of the containers is responsive to the depth of liquid in the corresponding tank, and both containers being connected to the lever.
